UNITED STATES PATENT OFFICE.

WILLIAM E. DE WITT, OF CHICAGO, ILLINOIS.

DESIGN FOR A GRIP FOR HANDLE-BARS.

SPECIFICATION forming part of Design No. 31,050, dated June 20, 1899.

Application filed May 22, 1899. Serial No. 717,859. Term of patent 14 years.

To all whom it may concern:

Be it known that I, WILLIAM E. DE WITT, a citizen of the United States, residing at Chicago, in the county of Cook and State of Illinois, have invented and produced a new and original Design for a Grip for Handle-Bars, of which the following, in connection with the accompanying drawing, is a full, clear, and exact specification.

- 10 The said drawing represents a handle-bar grip in perspective embodying my design. The leading features of my design consist of the grip proper, A, and the globular or ball-like portion B thereon.
- 15 The grip proper is an elongated handle-like portion cylindrical in cross-section and

slightly thicker at its mid-length than at its two ends, and the part B is a sphere apparently joined to one end of the part A, so that the two together present the appearance of a ball with one end of the part A projecting into it. The other end of the part A bears an ornamental ferrule C.

Having thus described my invention, what I claim as new therein, and desire to secure by Letters Patent, is—

The design for a grip for handle-bars substantially as herein shown and described.

WM. E. DE WITT.
